J. H. Clegg,

UNITED STATES PATENT OFFICE.

FRANK M. WEBSTER, OF WELLESLEY FARMS, MASSACHUSETTS, ASSIGNOR TO W. D. CASHIN CO., OF BOSTON, MASSACHUSETTS, A CORPORATION OF MASSACHUSETTS.

BOILER FEEDER.

Application filed July 29, 1926. Serial No. 125,747.

This invention relates to boiler feeders of the general type used to control the feeding of water to a boiler from a city main or from any other source under pressure. While devices of this kind ordinarily are referred to as boiler feeders, they are equally adapted for use in feeding water to tanks or any other apparatus where it is desired to maintain a substantially constant level.

10 It is the chief object of the present invention to devise a boiler feeder which will automatically maintain the water in the boiler at an efficient operating level notwithstanding conditions, such as surging, which introduce difficulties in the operation of such a mechanism. The invention also aims to devise a boiler feeder which will be unusually reliable in operation, will be simple in construction, and can be manufactured eco-

20 nomically.

The nature of the invention will be readily understood from the following description when read in connection with the accompanying drawings, and the novel features 25 will be particularly pointed out in the appended claims.

In the drawings,

Figure 1 is a central, vertical, cross-sectional view of a boiler feeder embodying this 30 invention; and

Fig. 2 is a cross-sectional view on the line 2—2, Fig. 1.

The apparatus shown comprises a float chamber casing 2 which is adapted to be connected by pipes 3 and 4 with the steam and water spaces, respectively, in a boiler, the casing being located at approximately the water level which is to be maintained. This casing is provided with openings at opposite sides thereof, one of these openings normally being closed by a cover 5, while the other is closed by the plate-like member 6 of a valve casing 7. Water from the city main or from any other suitable source of supply 40 is conducted to the valve casing 7 by a pipe 8, and additional pipe connections, including the pipe 9, conduct the water from this valve casing to the boiler. Slidably mounted in the valve casing 7 is a main valve 45 which controls the flow of water from the inlet port 11 to the outlet port 12. This valve fits rather loosely in the casing so that water under pressure can find its way up

55 behind the valve 10 into the valve chamber 14, and this pressure is relied upon chiefly to seat the valve. A coiled spring 15 which is interposed between the valve and a cap 16 threaded into the upper part of the valve chamber also tends to seat the valve.

This general type of valve is well known 60 and is arranged to be opened or closed by the pressure of the water in the supply thereto. For this purpose the valve chamber 14 is connected with the float chamber 17 in the casing 2 by means of a port or passage 18. 65 Normally, however, this passage is closed by a valve comprising a plunger 19 and a valve disk or plug 20 carried thereby, this plunger being supported in a tubular housing 21 which projects into the float chamber from 70 the valve casing and preferably is integral with said casing. A spring 22 tends to hold this valve in its closed position, and an adjustable cap 23 backs up the spring and is threaded into the housing 21, this cap being 75 secured in its adjusted position by a lock nut 24.

Mounted in the casing 2 is a float 25 preferably threaded on the end of a short pipe or tube 26 which, in turn, is threaded into 80 the end of a yoke or lever 27. This yoke terminates in a T-shaped head which is fulcrumed on a shaft or pin 28 that is supported by two lugs projecting inwardly from the valve casing plate 6, one of these lugs being 85 shown at 30. A pin or projection 31 extends laterally from the valve plunger 19 and is arranged to be engaged at certain times by the upper arm of the T-shaped lever 27.

Normally the level of the water is such 90 that it holds the float 25 in a position approximately as shown in Fig. 1, the upright arm of the lever 27 being out of engagement with the pin 31. When the level of the water in the boiler, and consequently, the 95 level in the float chamber 17, drops below a predetermined point, the resultant lowering of the float 25 causes the upright arm of the lever 27 to engage the pin 31 and move it backwardly or toward the right, Fig. 1. This 100 moves the valve 19 toward the right, thus allowing the water in the valve chamber 14 to escape through the duct 18 into the float chamber 17. It will be observed that a plurality of holes are drilled laterally through 105 the wall of the housing 21 where it joins

the plate 6, so that a very slight unseating movement of the valve 19 (usually referred to as the "pilot valve") affords relatively free escape for the water which has been 5 confined in the valve chamber 14.

The pressure of the water in the inlet port 11 immediately lifts the valve 10 off its seat, due to the fact that the pressure behind the valve has now been relieved, and water then 10 can flow freely from the supply pipe 8 through the valve casing 7 to the pipe 9 and into the boiler. This results in raising the level of the water in the float chamber and when the float has risen far enough to cause 15 the upright arm of the lever 27 to move out of contact with the pin or projection 31, the spring 22 seats the pilot valve 19, thus closing the duct 18 again. Water from the supply quickly builds up a pressure in the chamber 20 14 behind the valve 10, which pressure, combined with that of the spring 15, is sufficient to close or seat the valve, thus interrupting the flow of water to the boiler. These operations continue uninterruptedly according to the requirements of the boiler.

It sometimes happens that water is carried out of the boiler in considerable quantities into the heating system, and later returns to the boiler again, the boiler feeder in the mean- 30 time having operated to maintain substantially a predetermined level in the boiler. This returning water raises the level in the boiler excessively, and it is desirable for efficient operation to drain off some of this water.

For this purpose an overflow valve 33 has been provided, this valve normally closing an overflow port or outlet 34 which communicates with an overflow pipe 35, Fig. 2. The valve 33 is constructed substantially like the 35 pilot valve 19 and is slidably mounted in a tubular housing 36 integral with the valve casing 7. A cap 37 is screwed into the end of this housing and backs up a spring 38 which normally holds the valve 33 seated. A pin 39 projects laterally from the valve 33 through a slot in the housing 36 and is arranged to be engaged by an arm 40 projecting downwardly from the lever 27. Such engagement, however, takes place only when the level of the water in the 40 float chamber 17 is abnormally high, but when this engagement occurs it unseats the valve 33, thus allowing water to escape through holes in the housing 36 and through the outlet 34 into the overflow pipe 35 which leads to a drain, sump, or the like.

It will be observed that the pins or projections 31 and 39 are so located that the float 25 can have considerable freedom of movement without operating either the pilot valve 19 or 45 the overflow valve 33. In other words, there is considerable lost motion between these valves and the lever 27 which operates them. Consequently, the surging that frequently occurs in a boiler will not result in flooding the boiler, 50 which is an objectionable feature of many

boiler feeders. Neither will such surging operate the overflow valve under conditions which might result in draining the boiler to an undesirable degree.

Due to the fact that both the pilot and 70 overflow valves are carried by the casing 7 and main valve 10, the manufacture and assembly of the valve mechanism is greatly facilitated, such assembly being completed before the valve casing is bolted to the float 75 chamber casing 2. The invention thus provides a very simple and compact construction which can be manufactured economically and in which repairs can be made very easily in case they become necessary.

While I have herein shown and described the best embodiment of my invention that I have so far devised, it will be understood that the invention may be embodied in other forms without departing from the spirit or scope 85 thereof.

Having thus described my invention, what I desire to claim as new is:

1. In a boiler feeder, the combination of a main valve controlling the flow of water to the boiler and arranged to be opened or closed by the pressure of the water supply, a pilot valve operable to relieve said pressure on one side of said main valve, and overflow valve, and a single float controlling the 90 operation of both said overflow valve and said pilot valve.

2. In a boiler feeder, the combination of a main valve controlling the flow of water to the boiler and arranged to be opened or closed by the pressure of the water supply, a pilot valve operable to relieve said pressure on one side of said main valve, an overflow valve, a 100 float, and connections whereby said float is operable to open either said overflow valve or said pilot valve upon predetermined changes in the elevation of the float.

3. In a boiler feeder, the combination of a main valve controlling the flow of water to the boiler and arranged to be opened or closed by the pressure of the water supply, a pilot valve operable to relieve said pressure on one side of said main valve, an overflow valve, a float, and lost motion connections between said float and said pilot and overflow valves whereby said float is operable to open either said pilot or overflow valve but is permitted to have considerable freedom of movement without operating either of them.

4. In a boiler feeder, the combination of a main valve controlling the flow of water to the boiler and arranged to be opened or closed by the pressure of the water supply, a pilot valve operable to relieve said pressure on one side of said main valve, an overflow valve, 110 springs tending to hold said overflow and pilot valves closed, a float, and connections for causing said float to open either of the latter valves depending upon its position, 115 said connections being arranged to allow the 120

float to have a limited freedom of motion without opening either said overflow or pilot valves.

5. In a boiler feeder, the combination of a casing having a float chamber therein, a float in said chamber, a valve casing having water inlet and outlet ports therein, a main valve controlling the flow of water through said outlet port and normally held in its closed position through the aid of fluid pressure in said valve casing behind said valve, a pilot valve for relieving said pressure, a spring tending to hold said pilot valve closed, a projection extending laterally from said pilot valve, and a lever connected with said float and arranged to engage said projection to open said pilot valve.

6. In a boiler feeder, the combination of a casing having a float chamber therein, a float in said chamber, said casing having an opening in one side thereof, a valve casing secured to said float chamber casing and closing said opening therein, said valve casing having water inlet and outlet ports, a main valve controlling the flow of water through said outlet port and normally held in its closed position through the aid of fluid pressure in the valve casing behind said valve, said valve casing having a port therein leading from behind said valve to said float chamber

ber and also having an outlet leading from said float chamber, a pilot valve for closing said port, an overflow valve for closing said outlet, and connections whereby said float is operable to open said pilot valve when the water in said chamber is abnormally low and to open said overflow valve when the water in said chamber is abnormally high.

7. In a boiler feeder, the combination of a casing having a float chamber therein, a float in said chamber, said casing having an opening in one side thereof, a valve casing secured to said float chamber casing and closing said opening therein, said valve casing having water inlet and outlet ports, a main valve controlling the flow of water through said outlet port and normally held in its closed position through the aid of fluid pressure in the valve casing behind said valve, said valve casing having a port therein leading from behind said valve to said float chamber and also having an outlet leading from said float chamber, a pilot valve for closing said port, an overflow valve for closing said outlet, and a lever fulcrumed between said pilot and overflow valves and having two arms for operating said valves respectively, said float being connected to said lever and arranged to operate the lever.

FRANK M. WEBSTER.
